DOUBLE TERMINAL CONNECTOR

Marion W. Morris, Logansport, Ind., assignor to
 R-B-M Manufacturing Company, Logansport,
 Ind., a corporation of Indiana

Application October 28, 1935, Serial No. 46,968

8 Claims. (Cl. 173—328)

This invention relates to connecting means, and has to do with a double terminal connector for electrically connecting the terminals of two conductors.

It is frequently necessary as, for example, in automobile terminal blocks, to provide means for connecting together in pairs a plurality of conductors. My invention is directed to connector means particularly suitable for this purpose. It is an object of my invention to provide a terminal connector which is of simple construction and relatively inexpensive, and which provides means for effecting connection to a conductor with expedition and facility. A further object is to provide a connector of this character particularly suitable for establishing electrical connection between a pair of conductors. It is also an object of my invention to assure adequate electrical contact between the connector and a terminal member inserted therein, while eliminating possibility of loosening of the connection by vibration or changes of temperature. A further and important object of my invention is to provide a terminal receiving member having an opening for reception of a terminal member, and holding means associated with the opening in such manner as to be effective for holding the terminal member within the receiving member, while permitting insertion or removal of the terminal member by simple endwise movement thereof, the holding member being displaced to permit of insertion or removal of the terminal member by this endwise movement of the latter. Further objects and advantages of my invention will appear from the detail description.

In the drawing:—

Figure 1 is an isometric front view, on an enlarged scale, of a terminal connector embodying my invention secured upon a mounting plate;

Figure 2 is a front view, also on an enlarged scale, of a double terminal connector embodying my invention, mounted upon a mounting plate, the mounting plate being shown fragmentarily and the connector being partly broken away;

Figure 3 is a sectional view taken substantially on line 3—3 of Figure 2, certain parts being shown in elevation, this view also showing a conductor with a terminal member applied thereto and in operative relation to the connector, the terminal member being shown as partly broken away and in section;

Figure 4 is a sectional view taken substantially on line 4—4 of Figure 3.

The connector comprises a housing formed by two metal plates 1 and 2 which, for purposes of

description, may be designated the front plate and the back plate, respectively. Plate 1 is provided with two outwardly projecting cylindrical collars 3 of appreciable length, these collars defining two openings through plate 1, one adjacent the upper end of this plate and the other adjacent the lower end thereof. Plate 1 is of elongated rectangular shape, as shown, and is provided at its lower end with an integral base element 4 extending rearwardly of plate 1 at right angles thereto, the rearward end of this base element being provided with an integral downwardly directed tongue 5. Preferably, base element 4 is integral with plate 1, and collars 3 are formed integrally with this plate by suitably drawing, extruding or spinning the metal about the margin of a smaller aperture which is first punched in the plate. These elements may be formed separately and suitably secured to plate 1 if desired.

Plate 2 conforms in size and shape to plate 1 and is provided with side flanges 6 and a top flange 7, these flanges contacting the rearward face of plate 1 and spacing plate 2 therefrom. The plates 1 and 2 are thus spaced apart and define the housing referred to. Plate 2 is further provided, at its upper end, with a tab 8 integral with flange 7 and extending from the forward edge of this flange at right angles to plate 2. Tab 8 comprises a head 9 and a restricted neck 10 which fits snugly into a corresponding slot 11 formed in the upper end of plate 1 centrally thereof. This provides means effective to hold the plates against movement away from each other at their upper ends, while permitting relative endwise movement of these plates in the assembling thereof to provide a space therebetween for a purpose which will be apparent hereinafter. Plate 2 is provided with two circular openings 12 aligned with collars 3 and of the same diameter as the interior diameter of the respective collars. At its lower end plate 2 is provided with an integral base element 13 disposed at right angles thereto and seating upon the upper face of base element 4 of plate 1.

The housing thus formed is secured to a mounting plate 14, which may be the mounting plate of an automobile terminal block, conveniently by means of a hollow rivet 15 passing through plate 14 and base elements 4 and 13 of plates 1 and 2, respectively. In this manner, the housing is secured to the mounting plate, the securing means also being effective to prevent relative lengthwise movement between plates 1 and 2, thus maintaining these plates in proper assembled relation. Mounting plate 14 is provided

with a slot 16 which receives tongue 5, the slot corresponding in width to this tongue. This provides means effective to prevent turning of the housing about rivet 15, thus assuring that the housing is maintained in proper relation to the mounting plate. Other suitable means, such as two rivets 15, may be provided for securing the housing to the mounting plate though, ordinarily, I prefer to employ the means shown for this purpose, since this means is both simple and relatively inexpensive while being highly efficient.

The terminal holding means is disposed within the housing defined by plates 1 and 2. Preferably, this holding means comprises a spring member 17 formed from stiff spring wire of circular cross-section and suitable gage and is positioned in the space between the front and back members 1 and 2. Member 17 is shaped to provide, at each end thereof, an eye 18, each of 20 the eyes extending about the major portion of the adjacent pair of aligned openings through the housing. It will be noted that the eyes are oppositely related, terminal portion 18a of the upper eye 18 extending across the upper pair of 25 openings adjacent the lower side thereof and substantially chordally of these openings, terminal portion or element 18a of the lower eye 18 being disposed so as to extend across the lower pair of openings adjacent the upper side and substantially chordally thereof. Elements 18a 30 of the eyes 18, which elements may be defined as holding elements for retaining the conductor terminal members in the connector, are thus disposed adjacent one side of the respective pairs 35 of openings and remote from the other side thereof, while being displaceable toward the adjacent side of the openings and yieldingly urged toward the other side thereof. These holding elements are preferably of circular cross-section, as above noted, to facilitate insertion of the terminal members into the connector while permitting withdrawal therefrom of the terminal members when desired, in a manner to be hereinafter described. It will be understood, however, that my 45 invention, in its broader aspects, contemplates having these holding elements of circular or any other suitable cross-section.

Spring member 17 is substantially equal in length to the interior height of the housing so that the ends of this member preferably contact the end walls of the housing, as shown in Figure 2. The maximum width of member 17, determined by the width of the eye members 18, may be slightly less than the interior width of 55 the housing in order to obtain the full benefit of the spring of the eye members. This difference in width, however, is so slight as to prevent any objectionable displacement of member 17 transversely of the housing. In this manner, the 60 spring holding member 17 may be, and preferably is, unsecured to the housing, but is effectively held thereby against displacement. The interior depth of the housing, between plates 1 and 2 thereof, corresponds approximately to the 65 thickness or diameter of holding member 17, it being understood, however, that this member does not fit the housing, at the front and back thereof, so snugly as to in any way cause binding of member 17 within the housing. Preferably, a slight clearance is provided between spring 70 17 and the front and back walls of the housing, sufficient to prevent interference with the operation of the spring or holding member 17 while effectively eliminating any possibility of objectionable displacement of this member 17 either

forwardly or backwardly of the housing. In assembling the connector, member 17 may be placed between the flanges of plate 2, after which plate 1 may be assembled in operative relation to plate 2, the connector being then secured to mounting plate 14 in the manner previously described. Member 17 is preferably formed in the manner shown and above described, though, in the broader aspects of my invention, any suitable holding means for retaining the terminal members in the connector may be provided.

In Figure 3 I have shown a tip or terminal member 19 particularly suitable for use with the connector of my invention. This terminal member comprises a body portion 19, conveniently of cylindrical shape and corresponding in diameter to openings 12 and the interiors of collars 3 of the housing. The terminal member may be formed of any metal suitable for the purpose and body 19 thereof is provided, at its outer end, with an outwardly tapering nose element 20 which constitutes, with body 19, a structure of bullet form. The diameter of nose element 20, at the outer end thereof, is less than the distance between holding element 18a and the opposite side of the pair of openings through the housing adjacent the holding element. This permits of insertion of the terminal member through the aligned openings of the housing, no other action being necessary for securing the 30 terminal member in the housing, as will be later described.

Body 19 of the terminal member is provided with a circumferential groove 21 of rounded cross-section adapted for reception of the holding element 18a. At its inner end body 19 is provided with a base element 22 of increased diameter providing a shoulder 23 at the inner end of body 19 and extending outwardly therefrom radially thereof. This terminal member is secured 40 upon a conductor 24 of known type which includes a multiple strand wire or core 25 provided with a suitable covering 26 of insulation. The insulation 26 is removed from the end portion of core 25 for a suitable length thereof and the terminal member is then placed upon this end of the conductor with wire 25 extending through the outer end portion of nose element 20, the latter being provided, at its outer end, with a bore of approximately the same diameter as that of the 50 wire. Nose element 20 is then secured upon wire 25 by crimping, so as to displace inwardly thereof projections or elements 27 which are forced into the wire 25 and effectively secure the terminal member thereto. With the terminal member secured upon wire 25 in the manner shown in Figure 3 and above described, base element 22 of the terminal member constitutes a 55 protecting sleeve extending about the adjacent end portion of the insulating covering 26 for the 60 conductor.

In order to connect the conductor 24 to the connector, the terminal member is inserted through collar 3 of plate 1 and the aligned opening 12 of plate 2. During the first portion of the insertion of the terminal member, holding element 18a is displaced toward the adjacent side of the openings in the housing and, when groove 21 reaches the plane of holding element 18a, the latter snaps into this groove, thus securing the 65 terminal member within the connector. During the major portion of the insertion of the terminal member, collar 3 serves as a guide and thus facilitates insertion of the terminal member. When the terminal member has been fully in- 70 75

5 serted, body portion 19 thereof is held in tight contact with plate 2 and collar 3 at the portions thereof opposite to the holding member, due to the spring action of the latter previously referred to and the fact that the diameter of body 19 of the terminal member, at the bottom of groove 21, is slightly greater than the distance between holding element 18a and the opposite side of the openings in the housing associated therewith. Since the holding element 18a is of 10 circular cross-section, and the groove 21 in body 19 of the terminal member is of rounded cross-section, the terminal member may be withdrawn from the connector by exerting pull on conductor 24, the pull required for this purpose being appreciable but not excessive. The terminal member is thus effectively held in the connector and may be inserted into and withdrawn therefrom by simple endwise movement, no other action 15 being required. Since the body portion 19 of the terminal member fits within collar 3, adequate area of contact of the terminal member with the connector is provided.

20 The connector shown is intended for connecting two conductors, it being understood that a terminal member, secured upon a conductor in the manner disclosed, is inserted through each pair of aligned openings of the connector. Preferably, the terminal members are inserted through the connector from the front thereof, as shown in Figure 3. It will be understood, however, that, if required, either one of the terminal members may be inserted through the connector from the back thereof. In either case, body 19 of the terminal member extends into collar 3 for substantially the full length thereof, the elements of the terminal member being suitably proportioned for this purpose, thus assuring adequate contact surfaces between the terminal member and the connector. It will also be noted that the collar 3 is effective in preventing objectionable looseness or play, radially, of the terminal member in the connector, and the holding element 18a and groove 21 cooperate to prevent endwise movement of the terminal member.

45 The collars 3-3 are not strictly necessary but are desirable. They serve as guides for the introduction or removal of the tips t. They also tend to hold the tips in axial alignment with the hole even though there is considerable play or freedom 50 to permit easy insertion or removal of the tips t.

55 These collars also serve in connection with tips t, which are standard for certain purposes, to space the shoulder 23 properly so that groove 21 will register with the spring contactor 18a.

If a tip t with a shorter shank be employed so that the shoulder 23 comes against the flat surface of the plate the collars 3-3 may be omitted.

60 It will be observed that the insertion of the tips in both holes tends to increase the tension of the spring against the tips rather than to weaken it although each spring is ample within itself for making proper contact.

The holes and tips are fairly loose and do not 65 need to constitute a sliding fit. The spring contacts are stiff enough however to hold the tips t locked in place with sufficient rigidity that vibration is not effective to change or impair the contact.

70 What I claim is:—

1. In combination in means of the character described, a housing having two pairs of aligned openings for reception of terminal members, and a spring wire formed into a flat shape and confined within said housing against displacement,

5 said spring wire being shaped at each end to provide an eye, said eyes extending about the major portions of the respective pairs of openings and having terminal holding elements extending across said pairs of openings adjacent one side of each pair.

2. In combination in means of the character described, a housing having two pairs of aligned openings for reception of terminal members, and a spring wire within said housing free therefrom 10 and formed into a flat shape and confirmed thereby against displacement, said spring wire being shaped at each end to provide an eye, said eyes extending about the major portions of the respective pairs of openings and having terminal 15 holding elements extending across said pairs of openings adjacent one side of each pair.

3. In combination in means of the character described, a housing comprising two plates spaced apart and provided at one end with cooperating 20 means holding said plates against relative movement away from each other while permitting relative endwise movement of said plates for assembling them, said plates having aligned openings for reception of a cylindrical terminal member, said openings being of substantially the same diameter as said terminal member, holding means comprising a yielding holding element within said housing extending across said openings, a mounting plate, and means securing said 25 housing to said mounting plate and effective to prevent relative endwise movement of said housing plates.

4. In combination in means of the character described, a housing comprising two plates, one 30 provided with side and end flanges spacing it from the other, said one plate being provided at its upper end with a tab extending substantially at right angles thereto and having a reduced 35 neck, said other plate having a slot receiving said neck, each of said plates being provided at its lower end with a base element extending substantially at right angles thereto, the base element of said one plate seating upon the base element of said other plate, said plates having aligned 40 openings for reception of a terminal member, holding means comprising a yielding holding element within said housing extending across said openings, a mounting plate, and means securing 45 said base elements together and to said mounting 50 plate.

5. A terminal connector comprising, in combination, a housing formed of conducting material and having two pairs of aligned openings for receiving terminal members, guide means integrally formed with said housing and individual to each of said pairs of openings for guiding and bracing said terminal members into operative position, and a spring wire formed into a flat shape and disposed within said housing having 55 an eye member at each end, a portion of each of which extends across each of said pairs of openings adjacent one side thereof for urging said terminal members into contact engagement with said housing and said guide means.

6. A terminal connector for connecting a pair of cylindrical terminal members having circumferential grooves therein comprising, in combination, a housing formed of conducting material and having two pairs of circular openings of 70 slightly greater diameter than said terminal members for receiving them, and a spring wire formed into a flat shape and disposed within said housing having an eye member at each end, a portion of each of which extends across each 75

of said pairs of openings adjacent one side thereof for engaging said grooves and urging said terminal members into contact engagement with said housing.

5. 7. A terminal connector comprising, in combination, a pair of metal plates, means securing said plates in slightly spaced apart relation and parallel to each other, each of said plates having a pair of apertures in alignment with corresponding apertures in the other plate for receiving a pair of correspondingly shaped terminal members, and a spring wire formed into a flat shape and having a thickness slightly less than the spacing between said plates and eye portions at the ends thereof positioned between said plates with the eye portions in register with each pair of aligned apertures and having a portion

extending across each of said apertures for yieldingly holding said terminal members in position.

8. A terminal connector comprising, in combination, a metal housing having front and back walls spaced slightly apart and two pairs of aligned apertures therein for receiving a pair of correspondingly shaped terminal members, and a spring wire formed into a flat shape and having a thickness slightly less than the spacing between said plates and eye portions at the ends thereof positioned between said plates with the eye portions in register with each pair of aligned apertures and having a portion extending across each of said apertures for yieldingly holding said terminal members in position.

of said pairs of openings adjacent one side thereof for engaging said grooves and urging said terminal members into contact engagement with said housing.

5. 7. A terminal connector comprising, in combination, a pair of metal plates, means securing said plates in slightly spaced apart relation and parallel to each other, each of said plates having a pair of apertures in alignment with corresponding apertures in the other plate for receiving a pair of correspondingly shaped terminal members, and a spring wire formed into a flat shape and having a thickness slightly less than the spacing between said plates and eye portions at the ends thereof positioned between said plates with the eye portions in register with each pair of aligned apertures and having a portion

extending across each of said apertures for yieldingly holding said terminal members in position.
